UNITED STATES PATENT OFFICE.

ASA W. THOMPSON, OF MONMOUTH, ILLINOIS.

CHECK-ROWER.

SPECIFICATION forming part of Letters Patent No. 289,468, dated December 4, 1883.

Application filed July 14, 1883. (No model.)

To all whom it may concern:

Be it known that I, ASA W. THOMPSON, a citizen of the United States, and a resident of Monmouth, in the county of Warren and State 5 of Illinois, have invented certain new and useful Improvements in Check-Rowers; and I do hereby declare that the following is a full, clear, and exact description of the invention, which will enable others skilled in the art to 10 to which it appertains to make and use the same, reference being had to the accompanying drawings, which form a part of this specification, and in which—

Figure 1 is a perspective view of my improved check-rower. Fig. 2 is a rear view of the cam and seed-slide operating mechanism. Fig. 3 is a detail view of the cam. Fig. 4 is a front view of the cam and the bifurcated arm operated by the same. Fig. 5 is a top 20 view of the entire mechanism, and Fig. 6 is a detail view of the wire and a knob.

Similar letters of reference indicate corresponding parts in all the figures.

My invention has relation to check-rowers; 25 and it consists in the improved construction and combination of parts of the same, as hereinafter more fully described and claimed.

In the accompanying drawings, the letter A indicates a portion of the planter-frame upon 30 which the seed-boxes B are fastened, having a reciprocating slide, C, sliding in the bottoms of the same, and having a bar or cross-piece, D, fastened upon their tops. Two cross-pieces, E, are fastened upon the ends of this bar and 35 form bearings F, in which the check-shaft G turns, and are provided upon their ends with upwardly-projecting arms H, upon the ends of which the pulleys I, guiding the rope or wire, are journaled. Upon the ends of the 40 shaft are fastened two disks, J, having four, or more or less, bifurcated arms, K, extending from their periphery, through which arms the knotted check-rope passes, turning the disk one-fourth revolution for each knot. A cylinder, 45 L, having its ends cut to form each two diametrically-opposite curved points and two curved hollows, M and N, is secured upon the center of the shaft, the points upon one end of the cylinder or cam corresponding to the curved 50 hollows upon the other end, and the points and hollows corresponding to the arms upon the ends of the shaft. The sides of the cylin-

der have four, or more or less, according to the number of arms, grooves O, parallel with the axis of the same, and extending from near 55 one end to near the other end, corresponding to the points and hollows upon the ends of the cylinder, and forming rounded recesses P at one end, from which oblique grooves Q extend, passing from near the end of one groove 60 to the end of the next groove, all the oblique grooves running parallel and the rounded recesses being in the same end of the grooves. A rock-shaft, R, is journaled in a transverse bearing upon the under side of the bar D, under 65 the center of the cylinder, and has a bifurcated arm, S, upon its rear end, the upwardly-pointed ends of which are provided with anti-friction rollers T, which bear against the waved ends of the cam-cylinder, which will rock the 70 arm and shaft, when revolved, the rounded points upon one side pushing the one end toward the side, when the other end of the arm will enter the corresponding rounded hollow, 75 rocking the arm to one side, when the following point upon the other end will push the arm to the other side, and so forth. The rear end of the rock-shaft is polygonous, and a crank, U, is adjustably fastened upon the same by means of a set-screw, W, while the pin X 80 upon the lower end of the crank fits into a slotted upright lug, Y, projecting from the seed-slide, which will be reciprocated as the shaft is rocked. An arm, Z, is pivoted at one end upon the bar D, rocking in a horizontal 85 plane, and has an upwardly-projecting lug, a, upon its free end, which lug projects into the grooves in the surface of the cam-cylinder in which it slides, a spring, b, serving to draw it back, sliding in the straight grooves after it 90 has reached the end of the oblique grooves, which spring is fastened to the outer end of the arm at one end and to the upper side of the bar upon the seed-boxes at the other end.

The knotted check-wire consists, preferably, 95 of a number of knobs, c, shaped like a shank-button, having a groove, d, around the body, passing through the shank, in which groove the wire is placed, forming a loop, the end of which is twisted around the wire at the upper 100 surface of the button, while the end of the other piece of wire (the other end of which is fastened to a button in the same manner) is fastened to the shank of the button, thus form-

ing a series of long links of wire, each link having a button.

I am aware that a locking mechanism consisting of a cam-cylinder having straight and inclined grooves in one of its heads, into which 5 grooves a lug projecting from the end of a spring-actuated lever slides, has been shown and claimed in my former Patent No. 277,856, and I therefore do not wish to claim such construction, broadly, in this case; but

What I claim, and desire to secure by Letters Patent of the United States, is—

1. The locking mechanism consisting of a cylindrical cam having grooves in its surface 15 parallel with the axis of the cylinder, forming rounded recesses at one end, and oblique parallel grooves passing from the rounded recesses, near the ends of the same, to the other ends of the grooves, and a pivoted arm having a 20 lug projecting into and traveling in the grooves, and a spring serving to draw the lug back in the straight grooves, as and for the purpose shown and set forth.

2. The combination of the cylindrical cam 25 having curved points and hollows upon its ends, the points and hollows upon the ends corresponding to each other, as described, and having grooves in its surface running parallel with the axis of the cylinder and correspond-

ing to the points and hollows upon the ends, 30 and parallel oblique grooves passing between the opposite ends of the straight grooves, the rock-shaft having the bifurcated arm provided with anti-friction rollers upon its ends bearing against the waved ends of the cylinder, and 35 the pivoted arm having the lug projecting from its free end, and having a spring fastened to its free end drawing it laterally, as and for the purpose shown and set forth.

3. The herein-described check-rower, 40 consisting of the revolving shaft, the bifurcated arms, the cam-cylinder having the waved ends, and the straight and oblique parallel grooves in its surface, the rock-shaft having bifurcated arm provided with anti-friction rollers, and 45 the crank, the seed-slide having slotted upright lug, the pivoted arm having projecting lug upon its free end, and the spring fastened to the free end of the arm and to the frame, all constructed and combined to operate as 50 and for the purpose shown and set forth.

In testimony that I claim the foregoing as my own I have hereunto affixed my signature in presence of two witnesses.

ASA W. THOMPSON.
